FOOTSTOOL

Walter Henry, Fall River, Mass.

Application March 30, 1939, Serial No. 265,042

1 Claim. (Cl. 155—169)

This invention relates to an improved footstool including an invertible frame and a removable and invertible double ended cushion adapted to be mounted therein.

5 It is a primary object of this invention to provide a novel piece of furniture in the form of a footstool and including an invertible frame for supporting a removable double ended cushion whereby the frame may be inverted for disposing either end of the cushion uppermost and in position for use.

A further object of the invention is to provide means for slidably and removably mounting a cushion in a frame to enable the cushion to be 15 readily removed for cleaning, reupholstering or replacing.

Still a further aim of the invention is to provide a novel footstool including a cushion having two oppositely projecting cushion portions 20 adapted to be covered with material of different color and design to match or blend with different pieces of furniture, with which the article is intended to be used, so that the footstool may be inverted when moved from one piece of furniture 25 to another and in either position the uppermost cushion portion will match or blend with the piece of furniture with which it is to be used.

Other objects and advantages of the invention will hereinafter become more fully apparent from 30 the following description of the drawing, which illustrates a preferred embodiment thereof, and wherein—

Figure 1 is a side elevational view of the footstool,

35 Figure 2 is an end view in elevation of the same,

Figure 3 is a top plan view of the same.

Figure 4 is a transverse vertical sectional view taken along the line 4—4 of Figure 1, and

40 Figure 5 is an enlarged fragmentary vertical sectional view showing the structure connecting the cushion and frame.

Referring more particularly to the drawing, wherein like reference characters designate like or corresponding parts throughout the different views, 45 10 designates generally the footstool including the frame and cushion, designated generally 11 and 12, respectively.

The frame 11 includes the corresponding side 50 members 13 each of which is provided at each end with the corresponding arcuately shaped diverging portions 14 and 15 forming legs which terminate in the rounded ends 16 and 17, respectively. The ends 16 and 17 project in opposite 55 directions to form feet for alternately supporting

the frame 11. The corresponding feet 16 and 17 of the side members 13 are connected by the rungs 18 which retain said members in spaced substantially parallel relationship. A corresponding longitudinally disposed flange or rib 19 is 5 mounted on the inner side of each of the members 13, for a purpose which will hereinafter be described.

The cushion 12 comprises an intermediate base member 20 from each side of which projects a 10 cushion portion, designated 21 and 22, respectively. Cushion portions 21 and 22 have the covers 23 and 24, respectively, the edges of which are secured by the fastenings 25 to the edges of the base member 20, adjacent each side thereof and 15 the space between each side of the base 20 and the covers 23 and 24 is filled with suitable packing 26. Two oppositely disposed edges of the base member 20 are provided with the longitudinal grooves 27 which are adapted to slidably engage 20 the flanges 19 for removably mounting the cushion 12 therebetween with either of the portions 21 or 22 uppermost.

The side members 13 are preferably provided with the brackets 28 disposed on the inner sides 25 thereof and at corresponding ends of the flanges 19 for limiting the sliding movement of the cushion 12 in one direction relatively to the frame 11 so that when the cushion 12 is abutting the brackets 28 it will be centrally disposed relatively 30 to the frame 11.

From the foregoing it will be seen, that the cushion 12 may be readily removed by sliding it relatively to the flanges 19, away from the brackets 28 to remove it through one end of the frame 35 11 or applied to the frame by reversing the procedure and when mounted therein will be supported by the flanges 19. The thickness of the cushion 12 in its entirety is substantially greater than the width of the side members 13 so that 40 the cushion portions 21 and 22 project beyond or beneath and above the longitudinal edges of the members 13. The coverings 23 and 24 are preferably of different color and design so that by inverting the footstool 10 from its position as 45 seen in Figure 1, resting on the feet 16 it will be disposed to rest on the feet 17 with the cushion portion 22 instead of the cushion portion 21 uppermost. Thus the covering of cushion portion 21 may correspond or blend with one piece of 50 furniture and the covering of cushion portion 22 with another so that by merely inverting the footstool its upholstery will correspond or blend with either piece of furniture with which it may be used. The flanges 19 and grooves 27 provide 55

means for readily removing or applying the cushion 12 to enable it to be easily removed and more thoroughly cleaned particularly in otherwise inaccessible portions.

5 Various modifications and changes in the precise construction and arrangement of the parts forming the article are contemplated and may obviously be resorted to, and the right is therefore expressly reserved to make such variations 10 and changes as do not depart from the spirit and scope of the invention as hereinafter defined by the appended claim.

I claim as my invention:

15 A footstool comprising a pair of spaced corresponding sides, each of said sides having corre-

sponding end portions formed with pairs of ar-
cuately shaped, diverging legs, the legs, of ad-
jacent end portions, projecting in opposite direc-
tions, and terminating in rounded ends forming
feet, rungs connecting the corresponding feet of 5
said sides, said sides each being provided with a
longitudinally disposed inwardly projecting rail;
a base member provided with grooves in its oppo-
site edges for slidably engaging said ribs for re-
movably mounting it thereon, and a cushion pro- 10
jecting from each side of said base member and
extending beyond corresponding longitudinal
edges of the intermediate portions of said sides.

WALTER HENRY. 15
